LIGHT PRODUCING APPARATUS FOR USE WITH PHOTOSENSITIVE MATERIALS

James G. Burnett, Cedar Grove, N.J., assignor to Pacer
Research & Development Corporation, New York,
N.Y., a corporation of New York

Filed May 27, 1963, Ser. No. 75,082

Term of patent 14 years

(Cl. D61—1)

FIG. 1

FIG. 3

FIGURE 1 is a front top perspective view of a light producing apparatus for use with photosensitive materials showing my new design;

FIGURE 2 is a rear top perspective view of the light producing apparatus for use with photosensitive materials; and

FIGURE 3 is a bottom view of the light producing apparatus for use with photosensitive materials.

I claim:

The ornamental design for a light producing apparatus for use with photosensitive materials, as shown.
